UNITED STATES PATENT OFFICE

140,460

DESIGN FOR AN ASH TRAY

Boris Blecher, Philadelphia, Pa.

Application November 25, 1944, Serial No. 116,544

Term of patent 14 years

(Cl. D85—2)

To all whom it may concern:

Be it known that I, Boris Blecher, a citizen of the United States and a resident of Philadelphia, county of Philadelphia, State of Pennsylvania, have intended a new, original, and ornamental Design for an Ash Tray, of which the following is a specification, reference being had to the accompanying drawing, forming a part thereof, wherein:

I claim:

The ornamental design for an ash tray, as shown.

BORIS BLECHER.
